Application April 9, 1949, Serial No. 1,884

Term of patent 14 years

(Cl. D57—1)

To all whom it may concern:

Be it known that we, Fred G. Gay, Jr., and Raymond F. E. Stegeman, citizens of the United States and residents of the town of Greece, county of Monroe, and State of New York, have invented a new, original, and ornamental Design for an Eye Protector, of which the following is a specification, reference being had to the accompanying drawing, forming a part thereof.

Fig. 1 is a front perspective view of an eye protector, showing our new design.

Fig. 2 is a fragmentary bottom plan view thereof.

Fig. 3 is a rear perspective view thereof.

We claim:

The ornamental design for an eye protector, substantially as shown.

FRED G. GAY, JR.

RAYMOND F. E. STEGEMAN.
